UNITED STATES PATENT OFFICE

157,774

SUCTION OPERATED FLOOR CLEANING
TOOL

Frederick K. Minerley, Chicago, Ill.

Application January 19, 1948, Serial No. 143,887

Term of patent 7 years

(Cl. D9—2)

To all whom it may concern:

Be it known that I, Frederick K. Minerley, a citizen of the United States and a resident of Chicago, Cook County, Illinois, have invented a new, original, and ornamental Design for a Suction Operated Floor Cleaning Tool, of which the following is a specification, reference being had to the accompanying drawing, forming a part thereof.

In the drawing:

Figure 1 is a side elevation of a suction operated floor cleaning tool, showing my new design;

Figure 2 is a front elevation of the suction operated floor cleaning tool; and

Figure 3 is a rear elevation of the suction operated floor cleaning tool.

I claim:

The ornamental design for a suction operated floor cleaning tool, as shown.

FREDERICK K. MINERLEY.
